UNITED STATES PATENT OFFICE.

WILLIAM SPARKS, OF JACKSON, MICHIGAN.

CONDUCTOR-COUPING.

1,034,159.

Specification of Letters Patent. Patented July 30, 1912.

Application filed April 4, 1912. Serial No. 688,430.

To all whom it may concern:

Be it known that I, WILLIAM SPARKS, of Jackson, in the county of Jackson, in the State of Michigan, have invented new and useful Improvements in Conductor-Couplings, of which the following, taken in connection with the accompanying drawings, is a full, clear, and exact description.

This invention relates to certain improvements in conductor couplings for electrically operated horns and similar instruments containing electrical apparatus to which current is supplied from an external source.

The main object is to provide a coupling composed of insulator sections containing the binding post of the electric conductors having slip connections one with the other so that the sections may be readily detached leaving the horn with a substantially smooth exterior capable of being easily cleansed or polished when desired.

In other words I have sought to provide a sectional coupling having one of its sections rigidly secured to the body of the horn with its outer end substantially flush therewith, while the other section is removable for the purpose not only of breaking the electrical connection between the inclosed apparatus and source of supply but also to obviate the inconvenience of projections from the surface of the horn during the cleaning operation.

Another object is to provide the horn with a metal sleeve adapted to be removably secured thereto for rigidly holding one of the insulator sections in fixed relation to the body of the horn.

Another object is to provide the insulator sections with removable caps one of which as the inner cap cooperates with the sleeve to hold the adjacent insulator section against endwise movement while the cap for the outer section serves to protect the adjacent binding posts or terminal connections of the wires against accumulations of moisture or other foreign matter which might tend to produce a short circuit.

Other objects and uses will be brought out in the following description.

In the drawings—Figure 1 is a face view of a portion of an electrically operated sound producing device for automobile horns showing my improved coupling in operative position. Fig. 2 is a plan of the same coupling showing the adjacent portion of the casing for the sound producing de-

vice or horn in section. Fig. 3 is a longitudinal sectional view through the same coupling and its support taken on line 3—3, Fig. 1. Figs. 4, 5, 6 and 7 are perspective views respectively of the inner insulating cap, the assembled insulator sections containing the slip terminal connections for the wires and the outer insulator cap. Fig. 8 is a plan of the part seen in Fig. 2 showing the insulator sections and slip terminal connections separated.

This coupling is adapted to be used more particularly in connection with the shells or hollow sections of horns or amplifiers containing electrically operated sound producing devices for automobiles, motor boats and similar uses, and comprises a metal supporting sleeve —1— and co-axial insulator sections —2— and —3— each containing a pair of terminals or binding posts —4— and —5— of brass, copper or other conducting material, the terminals of one section having slip connections with those of the other section.

The metal sleeve —1— which is substantially cylindrical is passed through and fitted closely within a corresponding opening in one side of an amplifier shell —6— and is provided at its outer end with a laterally projecting comparatively thin annular flange —7— abutting against the outer face of the shell —6— to limit the inward movement of the sleeve, said flange being provided in its periphery with one or more recesses or openings for the reception of screws —8— by which the sleeve is secured to the shell against rotation or outward axial movement. The inner end of the sleeve which extends some distance beyond the inner face of the shell is provided with an inwardly projecting flange —9— for engaging a corresponding annular shoulder —10— on the insulator section —2— to hold the latter against undue inward axial movement. The insulator section —2— is also cylindrical and adapted to fit snugly within the sleeve —1—, the distance between the outer end of this insulator section and shoulder —10— being substantially equal to the distance between the outer face of the sleeve —1— and shoulder —9— so that when these parts are assembled, the outer end face of the insulator section —2— is substantially co-incident or flush with the corresponding end face of the sleeve —1—. The inner end of the insulator section —2— extending be-

105
110

yond the shoulder —10— is reduced in diameter and threaded externally for receiving a hollow screw cap —11— also of insulating material and adapted to cover the inner ends of the terminals or binding posts —4—, said cap being provided with a central opening —12— for the passage of the wires as —13— therethrough. When the insulator cap —11— is screwed upon the inner end of the insulator section —2—, it engages with the inner end face of the sleeve —1— to hold the insulator section —2— against axial displacement outwardly.

The wire terminals or binding posts —4— are incorporated or embedded side by side within the insulator section —2— but are spaced apart from each other and from the outer side of the insulator section in parallelism with each other and with the axis of said section, and are therefore insulated from each other. The inner ends of these binding posts project a short distance beyond the corresponding end of the insulator section —2— and are provided with central sockets —14— for receiving the ends of the wires —3— which are held in place by binding screws —15— shown more clearly in Fig. 6. The outer ends of the binding posts are also provided with central lengthwise sockets —16— for receiving the reduced ends as —17— of the binding posts —5—. The binding posts —5— are also incorporated or embedded within the insulator section —3— some distance apart and parallel with each other and with the axis of said section so as to insulate them one from the other. The outer ends of these binding posts —5— project a short distance beyond the corresponding end of the insulator section —3— and are provided with central lengthwise sockets —18— for receiving the adjacent ends of electric wires —19— which may be connected to any source of current supply not necessary to herein illustrate or describe. The inner ends of the binding posts —5— extend some distance beyond the adjacent end face of the insulator section —3— and as previously stated are reduced in diameter to fit with an easy friction fit in the sockets —16— in the binding post —4—, thereby establishing a slip connection between the binding posts —4— and —5— and permitting the outer insulator section with its binding post —5— to be readily withdrawn from the fixed insulator section —2— and its binding posts —4—, thereby leaving the adjacent surface of the horn or amplifier —6— free from excessive projections for cleaning and polishing.

60 The inner ends of the wires —19— are secured in the sockets —18— of the binding post —5— by means of screws —22— as best seen in Fig. 6. The outer end of the

insulator section —3— is reduced in diameter and threaded externally for receiving a cap —20— which is similar to the cap —14— and interchangeable therewith, said cap —20— being provided with a central opening —21— for the passage of the wires —19— therethrough. These insulator sections —3— and —4— and their caps —14— and —20— serve to conceal the binding posts and to protect them from accumulations of dust and other foreign matter which might tend to cause short circuits, the outer sleeve —3— and its cap —20— serving as a convenient handle whereby the binding posts —5— may be withdrawn from or inserted into the corresponding binding post —4— to make and break the circuit. 80

When it is desired to clean or polish the surface of the horn or amplifier, the insulator sections —3— together with their binding posts —5— may be withdrawn entirely from the shell, thus leaving the surface of the latter practically smooth to facilitate the operation of cleaning or polishing without liability of breaking or overstraining the electrical connections, as would be the case if the binding posts were permanently secured to the exterior of the shell.

What I claim is:

A coupling for electric conductors comprising a metal sleeve having one end provided with an inturned annular shoulder, 95 means for securing the sleeve in a fixed position, an insulator section fitted within the sleeve and provided with a reduced threaded end forming an annular shoulder abutting against the annular shoulder of the sleeve, the opposite end of the insulator section being substantially coincident with the corresponding end of the sleeve, binding posts embedded in the insulator section and extending from the coincident end faces of the sleeve and insulator section some distance beyond the opposite end of said section, a cap of insulating material screwed upon the threaded end of said insulator section and against the annular shoulder of the sleeve to hold said insulator section and sleeve against relative endwise movement, an additional insulator section coaxial with the first named section, and a separate set of binding posts embedded in the additional 115 insulator section and having portions thereof in sliding frictional engagement with the binding posts of the first named insulator section.

In witness whereof I have hereunto set 120 my hand on this twenty fifth day of March 1912.

WILLIAM SPARKS.
